SHUTTER

Henry M. Vetterlein, Blasdell, N. Y., assignor of one-third to Henry Penn Burke, Philadelphia, Pa., and one-third to Harvey L. Hirst, River-ton, N. J.

Application September 28, 1939, Serial No. 296,887

5 Claims. (Cl. 268—30)

This invention relates to improvements in shutters for door or window openings, of the type in which the shutter proper comprises a curtain made of a plurality of sheet metal panels slidable vertically with respect to each other, which are adapted, when the door or window-opening is closed, to be disposed one below the other in overlapping relationship, and when the door or window opening is open, to be disposed one behind the other above the opening.

The present invention relates more particularly to improved means for raising and lowering the panels which comprise the curtain.

The principal object of the present invention is to provide, in a shutter of the character aforesaid, improved means for raising and lowering the curtain panels, which will be efficient in operation yet simple and inexpensive in construction.

A further object of the invention is to provide, in a shutter of the character aforesaid, improved operating mechanism by means of which the curtain panels will be raised and lowered in the proper sequence.

A further object of the invention is to provide, in a shutter of the character aforesaid, improved mechanism for raising and lowering the curtain panels, which may be actuated with a minimum of exertion on the part of the operator.

The nature and characteristic features of the invention will be more readily understood from the following description, taken in connection with the accompanying drawings forming part hereof, in which:

Figure 1 is an elevational view, looking from the interior of the building, of a door structure embodying the main features of the present invention;

Fig. 2 is a vertical central section thereof, with the curtain panels shown in the lowered or closed position;

Fig. 3 is a similar view, but with the curtain panels shown in the raised or open position;

Figs. 4 and 5 are side elevations, illustrating the arrangement of counterweights employed for counterbalancing the respective door panels, the counterweights being shown in said views in positions corresponding respectively to the positions of the door panels shown in Figs. 2 and 3;

Fig. 6 is a vertical section of the lower door panel and certain associated parts, illustrating details of construction;

Fig. 7 is an enlarged sectional view illustrating in detail certain portions of the operating mechanism;

Fig. 8 is a section taken approximately on the line 8—8 of Fig. 7; and

Fig. 9 is a section taken approximately on the line 9—9 of Fig. 8.

It should, of course, be understood that the description and drawings herein are illustrative merely, and that various changes and modifications may be made in the structure disclosed without departing from the spirit of the invention.

Referring to the drawings, 11 designates a wall forming part of a building and having therein a door or window opening 12 which the shutter is adapted to close. The shutter proper comprises a curtain made of a plurality of plates or panels 13 which are slidable vertically, being guided at their sides in the housings 14 and 15.

Each of the panels 13 of the shutter curtain has its upper end portion bent over at the top and then downwardly, as at 16, to form a channel along the upper edge of each panel, and likewise each of the panels, with the exception of the lowermost one, is bent inwardly at the bottom and then upwardly, as at 17, to form a channel along the bottom of each of said panels, the arrangement being such that, when said panels are lowered to the closed position, the downwardly extending part 16 of the bent-over portion at the top of each panel is adapted to engage the channel at the bottom of the adjacent panel to the front, and the upwardly extending part 17 of the bent-over portion at the bottom of each panel is adapted to engage the channel at the top of the adjacent panel to the rear.

The lowermost curtain panel 13^a is provided along its lower edge with an angle member 18 which is adapted to engage the floor or sill 19 of the door or window opening 12 when the panels 13 are lowered to the closed position.

There is also provided, at the top of the structure, a fixed panel 20 which has its lower end portion bent inwardly and then upwardly, as at 17^a, to form a channel along the bottom thereof for engagement, when the movable curtain panels are lowered, by the bent-over portion 16 at the top of the uppermost panel 13^b.

Each of the curtain panels, with the exception of the lowermost one, is provided with lugs or ears 21 extending inwardly so as to overlap in each instance the top of the adjacent panel to the rear, and thus prevent said panel to the rear from being raised above the panel in front of the same in any given position of said panels.

Each of the curtain panels 13, with the exception of the lowermost one 13^a, has connected

thereto, at a point midway the extremities thereof, a suitable cable chain 22 which extends upwardly therefrom and thence over an idler pulley 23 suitably supported at the top of the housing. Each chain 22, after passing from its idler pulley 23, extends horizontally above the top of the housing to a pulley 24 which is notched or toothed on its periphery complementary to the particular type of chain employed, whereby as each pulley is actuated, its chain is operated in unison therewith during the raising and lowering of the curtain panels, as will be hereinafter more fully set forth. Each of the pulleys 24 is journaled on a shaft 25 which in turn is journaled in bearing structures 26 and 27, suitably supported at the top of the housing.

After passing over its pulley 24, each of said chains then extends downwardly, having a counterweight 28 secured to the lower end thereof. While each of the curtain panels 13 is preferably provided with but a single chain 22 extending to its counterweight 28, it will, however, be understood that a plurality of such chains 22 and counterweights 28 may be employed for each panel, if desired.

The lowermost panel 13^a of the curtain is preferably provided near each end thereof with an inwardly extending bracket 29 to which cable chains 30 and 31 are respectively connected. The chains 30 and 31 extend over idler pulleys 32 and 33 respectively mounted at the top of the housing, and thence extend horizontally to a pulley 34 which is mounted on the shaft 25 and keyed thereto. The pulley 34 has two grooves in its periphery, each shaped complementary to the chain which passes thereover. The chains 30 and 31 after passing over the pulley 34 extend downwardly and are connected to a counterweight 35. The purpose of so mounting the chains, which are connected to the lowermost panel 13^a at the lower inner portion of said panel, is to permit the use, in the structure, of an automatic lock device of the type described and shown in Letters Patent, No. 2,007,552, dated July 9, 1935, if desired. Also the use of two chains connected to said panel insures the raising and lowering of the curtain panel without tilting lengthwise.

The shaft 25, upon which the pulleys 24 and 34 are mounted, extends through the bearing 26 which is secured to the top portion of the housing, and is provided on its projecting end with a suitable sheave 36 which is fixedly secured to the shaft 25 and is provided in its periphery with a groove notched complementary to an endless chain 37 which extends thereover. The endless chain 37 depends downwardly in a loop to a point for convenient operation. When said chain 37 is actuated in either direction, the shaft 25 upon which the sheave 36 is mounted will be constrained to rotate in a corresponding direction, and thus actuate the chains 30 and 31, and 22, which are connected to the respective curtain panels, in a manner to be hereinafter described.

As hereinbefore pointed out, the chain pulley 34, which is provided for the pair of chains 30 and 31 which are connected to the lowermost curtain panel 13^a, is keyed to the shaft 25, whereas each of the pulleys 24, over which pass the chains 22 which are connected to the curtain panels 13 other than the lowermost one, is so mounted on said shaft 25 as to permit said shaft, under certain conditions and at certain times, to be rotated independently thereof.

Each of the chain pulleys 24 is provided with a plurality of recesses in which are mounted plugs 38, of suitable friction material, which in each instance bear against the next adjacent pulley.

Mounted in the bearing 26 is a coil spring 39 which surrounds the shaft 25. Said coil spring 39 bears at one end against a washer 40 which in turn bears against the rearmost pulley 34 and at its other end against a bushing 41 which is threaded in the bearing. The arrangement is such that the bushing 41 may be adjusted in the bearing 26 to obtain the proper degree of tension of the coil spring 39, and thus regulate the frictional drag between the several chain pulleys.

A metallic washer 42 is interposed between the chain pulley 24 nearest the front end of the shaft 25 and the bearing 27 provided at that end of the shaft.

To prevent rattling of the curtain panels 13, in any given position thereof, the lowermost panel 13^a may be provided, at each end thereof, with the device, illustrated in Fig. 6 of the drawings, comprising a leaf spring 43, secured midway its extremities to said panel and carrying, at each end thereof, a roller 44 which rollers bear against the inner surface of the housings 14 and 15.

The operation of the device will now be explained.

Assuming the door to be closed, that is with the curtain panels 13 in the positions shown in Figs. 1 and 2 of the drawings, and it is desired to open the same by raising said panels to the positions shown in Fig. 3 of the drawings, the operator will now actuate the endless chain 37 in the proper direction, thereby rotating the sheave 36 over which said chain 37 passes. Said sheave 36, being fixedly mounted on the shaft 25, will cause said shaft to rotate, and thereby rotate the chain pulley 34 over which pass the two chains 30 and 31 extending from the lowermost of the curtain panels 13^a.

When the lowermost of the curtain panels 13^a is raised to such position that the top edge thereof bears against the overhanging lugs or ears 21 carried by the next adjacent curtain panel 13, said panel 13 will thereafter be raised, as the operator continues to actuate the endless chain. The same action occurs as the top edge of each panel 13 reaches and engages the overhanging lugs or ears 21 carried by the top edge of the next adjacent panel 13, until finally all of the panels are raised to the position shown in Fig. 3 of the drawings.

By reason of the peculiar action of the friction members 38 carried by the respective chain pulleys 24, the curtain panels 13 will be raised in successive order beginning with the lowermost panel 13^a.

To lower the curtain panels to close the door or window opening, the operator will actuate the chain 37 in the opposite direction, whereupon the friction members 38 carried by the chain pulleys 24 will first cause all of the panels to be lowered in unison until the bent-over portion at the top of the uppermost panel 13^b engages the upturned portion 17^a at the bottom of the fixed panel 20 at the top of the structure. The remaining panels 13 will then continue to be lowered until the bent-over portion 16 at the top of each panel reaches and engages the upturned portion 17 at the bottom of the adjacent panel to the front, this action continuing until the angle member 18 at the bottom of the lowermost

panel 13^a reaches the floor or sill 19 at the bottom of the door or window opening 12.

I claim:

1. In a shutter for door or window openings, a curtain comprising a plurality of panels adapted to be raised and lowered, individual counterweights for each of said panels, a cable extending from each of said panels to its respective counterweight, a pulley for each of said panels over which its respective cable extends, a shaft on which said pulleys are mounted, and means disposed between each adjacent pair of said pulleys for imparting a definite frictional drag therebetween.

2. In a shutter for door or window openings, a curtain comprising a plurality of panels adapted to be raised and lowered, individual counterweights for each of said panels, a cable extending from each of said panels to its respective counterweight, a pulley for each of said panels over which its respective cable extends, a shaft on which said pulleys are mounted, means disposed between each adjacent pair of said pulleys for imparting a definite frictional drag therebetween, and means for adjusting the degree of such frictional drag.

3. In a shutter for door or window openings, a curtain comprising a plurality of panels adapted to be raised and lowered, individual counterweights for each of said panels, a cable extending from each of said panels to its respective counterweight, a pulley for each of said panels over which its respective cable extends, a shaft on which said pulleys are mounted, means for rotating said shaft, the pulley for a cable extending from the lowermost panel being keyed to said shaft, and the shaft being rotatable with

respect to the other pulleys, and means disposed between each adjacent pair of said pulleys for imparting a definite frictional drag therebetween.

4. In a shutter for door or window openings, a curtain comprising a plurality of panels adapted to be raised and lowered, individual counterweights for each of said panels, a cable extending from each of said panels to its respective counterweight, a pulley for each of said panels over which its respective cable extends, a shaft on which said pulleys are mounted, means for rotating said shaft, the pulley for a cable extending from the lowermost panel being keyed to said shaft, and the shaft being rotatable with respect to the other pulleys, means disposed between each adjacent pair of said pulleys for imparting a definite frictional drag therebetween, and means for adjusting the degree of such frictional drag.

5. In a shutter for door or window openings, a curtain comprising a plurality of panels adapted to be raised and lowered, individual counterweights for each of said panels, a cable extending from each of said panels to its respective counterweight, a pulley for each of said panels over which its respective cable extends, a shaft on which said pulleys are mounted, means for rotating said shaft, the pulley for a cable extending from the lowermost panel being keyed to said shaft, and the shaft being rotatable with respect to the other pulleys, means disposed between each adjacent pair of said pulleys for imparting a definite frictional drag therebetween, and means for adjusting simultaneously the degree of frictional drag between all of said pulleys.

HENRY M. VETTERLEIN.
